CLAIM

The ornamental design for a plastic sheet with a surface pattern, as shown and described.

DESCRIPTION

FIG. 1 is a top view of a plastic sheet with a surface pattern; and,

FIG. 2 is an enlarged view of the plastic sheet with a surface pattern shown circumscribed within FIG. 1.

In FIGS. 1 and 2 the solid line area between the two broken lines depicts the claimed design. All other areas and all broken lines depict portions of the plastic sheet with a surface pattern that form no part of the claimed design.
